CLAMP

Frank C. Wallace, Los Angeles, Calif., assignor, by
mesne assignments, to Herman H. Helbush,
Beverly Hills, Calif.

Application August 22, 1942, Serial No. 455,760

3 Claims. (Cl. 85—5)

This invention relates to clamp devices. More particularly it has to do with improvements in skin clamps such as are employed for holding perforated sheets in superposed relation while they are being riveted.

It is among the principal objects of my invention to provide a clamp of this character which is self-contained in that it does not require any applying tool in connection with its operation; and which is particularly adaptable for heavy duty work requiring greater strength and pressures than are possible in the conventional clamp employing spring means to apply the clamping pressure.

Another object is the provision of a durable, economical and efficient skin clamp.

Still further objects and advantages are inherent in my invention and how those as well as the foregoing are achieved will be understood from the following detailed description of a presently preferred form of clamp in which my invention may be carried out, for which purpose I shall refer to the accompanying drawings, in which:

Fig. 1 is a side view partly in longitudinal section and partly in elevation;

Fig. 2 is a side elevation showing the clamp in the course of being applied to the work;

Fig. 3 is a side elevation showing the device in clamping position;

Fig. 4 is an end view;

Fig. 5 is a longitudinal sectional view, partly in elevation, showing a variational form; and

Fig. 6 is a section on line 6—6 of Fig. 5 but showing the spreading member retracted.

Referring now to the drawings, the numeral 5 designates a body or retaining member comprised of a threaded shank portion 6 and bifurcations or retaining pins 7, six bifurcations being here shown although a greater or lesser number may be employed. Member 5 has a longitudinal bore 8 and a longitudinal keyway 9 for the purpose to be described. Slidably longitudinally of the retaining member I provide a sleeve 15 having a hexagonal outer surface 16 and a circular sheet engaging end portion 17. To hold this sleeve against rotation with respect to the retaining member, I provide a key 18 which projects through a side wall of the sleeve and into the keyway 9.

Bifurcations 7 are provided with lateral projections 1a at their outer ends, which projections provide sheet engaging portions to engage the periphery of the perforation P provided through the sheet S', the sheet farthest from

the sheet engaging end portion 17 of the sleeve, and the bifurcations are preferably made resilient to permit them to flex together sufficiently to insert the retaining member through the registering perforations in the sheets (see Fig. 2).

A circular spreader 20 is slidably mounted in the bore of the retaining member, and has a stem 21 presenting a headed end 22 for manual operation. The spreader 20 is of relatively larger diameter than the stem and intersects the stem in a bevel 23 which engages the shoulder 24 in the retaining member to provide a stop against further movement in the direction of the headed end of the stem.

A nut 30 is threaded onto the threaded shank 6 of the retaining member and presents an integral operating handle 32 to facilitate manually turning the nut on the retaining member. Nut 30 has an undersurface 34 engageable against sleeve 15. The nut 30 and sleeve 15 cooperate as locking or securing means to secure the device in clamping position as will be hereinafter described.

The device operates as follows: First, to insert the bifurcations 7 in the registering perforations provided in superposed sheets S, S', the operator pulls stem 21 outwardly to slide the spreader 20 until it abuts the stop shoulder 24, in which position the spreader is out of spreading engagement with the bifurcations 7 (see Figs. 1 and 2). Then the bifurcations are inserted through the perforations (Fig. 2) and after being inserted until the sheet engaging surface 17 of the sleeve 15 rests against the adjacent sheet S (Fig. 3), the stem 21 is pushed inwardly to cause spreader 20 to slide longitudinally between the bifurcations and spread them radially apart, after which the nut 30 is turned by means of the handle 32 to draw the projections 1a against the periphery of the perforation in sheet S' and urge the sheet engaging surface 17 of the sleeve against sheet S, thus clamping together the superposed sheets, the retaining member and spreader acting to retain the perforations in register. After thus bringing the parts into clamping position the nut 30 and sleeve 15 serve to lock them in that position until released by turning handle 32.

The device is adaptable to clamping sheets of varying thicknesses since the sheet engaging sleeve 15 is slidable along the retaining member throughout the length of the keyway 9.

I provide the sleeve with a hexagon tool engaging surface in order to apply thereto a wrench if desired to hold the retaining member and

sleeve against rotation with respect to the sheets during rotation of the nut.

In Figs. 5 and 6, I show a variational form of my invention wherein the numeral 40 denotes a cylindric body, externally threaded at 41, and having an end wall 42 through which a hole 43 is provided. A sleeve 45 is longitudinally slidably mounted on the body and has an end wall 46 providing a work engaging surface. A nut 50 having a handle 51 is threaded onto the opposite end of the body and has a bottom surface 53 engageable against the inner end of the sleeve 45. The body is provided with a longitudinal slot 55 (Fig. 6) and a pin 56 extends through sleeve 45 into the slot to prevent rotation of the sleeve relative to the body but to permit relative longitudinal sliding movement therebetween.

The retaining member is comprised of two separate pins 60, 60a having enlarged outer ends 61 and plane inner faces 62, the inner ends of the pins being headed at 63, which heads seat against the inner surface of end wall 42.

An elongated spreader bar 70 is slidably mounted in the bore of the body and has a reduced end portion 71 which slides between the pins 60, 60a to expand the latter apart, the outer end portion 72 of the spreader bar providing an operating stem carrying a knob 73 secured thereon by a pin 74. Spreader portion 71 is longitudinally slotted at 75 and a cross pin 76 extends through registering holes in the body and pin head 63, the pin extending transversely through the slot. Thus pin 76 prevents relative movement as between the retaining pins and the body and, in cooperation with the ends of the slots 75, limits movement of the spreader bar.

The operation of the device of Figs. 5 and 6 is as follows: When the device is in the position of Fig. 6 the spreader is retracted from between the outer ends of the pins 60, 60a to permit the enlarged ends of the pins to be flexed together and inserted through perforations in sheets to be clamped together. After being thus inserted until the work engaging surface 46 of the sleeve abuts the adjacent face of the work, the spreader is pushed inwardly to the position of Fig. 5, in which position the spreader portion 71 moves the outer ends of the pins 60, 60a apart and then as the nut 50 is turned on the body, the enlarged ends 61 of the pins are drawn against the periphery of the perforation in which the retaining pins are inserted, thus clamping the work between the pin ends 61 and work engaging surface 46. To release the clamp, the spreader bar is again retracted to the position of Fig. 6.

While, in the foregoing description, I have resorted to considerable detail in order clearly to explain one specific form of device in which my invention may be carried out, I wish it understood that, in its broader aspects, my invention is not limited to such details.

I claim:

1. A clamp comprising an externally threaded cylindric body having an end wall with an opening therethrough, said body presenting a transverse hole through its side wall, a pair of retaining pins each having a headed inner end seating against the inner surface of the body end wall and an outer end projecting from the body, a spreader bar disposed longitudinally of the body for sliding movement between the retaining pins, a longitudinal slot in the spreader bar, a pin extending through the transverse hole in the body and through the inner ends of the retaining pins to secure the latter against longitudinal movement with respect to the body, a sleeve slidably longitudinally on the body, and nut means threaded onto the body and engageable against the sleeve whereby to cause relative longitudinal movement as between the retaining pins and sleeve.

2. A clamp comprising a cylindric exteriorly threaded body, a pair of retaining pins carried by and projecting from the outer end of the body, a spreader bar disposed longitudinally of the body for sliding movement between the retaining pins, said spreader bar having an integral portion projecting from the inner end of the body for manual manipulation, a sleeve mounted on the body for sliding movement axially thereof, and a wing nut threaded onto the body and engageable at its end against an end of the sleeve whereby to cause relative longitudinal movement as between the sleeve and body in response to rotation of the nut relative to the body.

3. A clamp comprising an externally threaded cylindric body having an end wall with an opening therethrough, a pair of retaining pins each having a headed inner end seating against the inner surface of the body end wall and an outer end projecting from the body through the opening, means securing the pins against longitudinal movement relative to the body, a spreader bar disposed longitudinally of the body for sliding movement between the retaining pins, a sleeve slidably longitudinally on the body, and nut means threaded onto the body and engageable at its end against an end of the sleeve whereby to cause relative longitudinal movement as between the sleeve and body in response to rotation of the nut means relative to the body.

FRANK C. WALLACE.
